UNITED STATES PATENT OFFICE

2,004,670

MANUFACTURE OF SOAP POWDERS

Charles Watson Moore, Warrington, Lancaster, and Horatio Ballantyne, Tadworth, Surrey, England, assignors to Lever Brothers Limited, Port Sunlight, England, a company of Great Britain

No Drawing. Application April 2, 1932, Serial No. 602,870. In Great Britain May 22, 1931

14 Claims. (Cl. 87—16)

This invention relates to the manufacture of soap powders of the kind known as perborate soap powders.

Such powders contain perborate (usually sodium perborate), soap and sodium silicate, and as a rule sodium carbonate, minor proportions of other suitable ingredients being sometimes present. Methods of producing the powders are well known. The characteristic bleaching properties (as distinct from the purely detergent properties) of the powders are dependent upon their content of "active" or "available" oxygen. As hitherto manufactured they possess the disadvantage that under certain conditions of storage, particularly when packed in cartons as is usual, they suffer a progressive, more or less gradual, decomposition of the perborate with corresponding loss of active oxygen. Further, it has been found that when they are put into use for washing purposes the bleaching action is frequently affected by the composition of the water employed, being least when the water is very soft and generally, but not always, greatest when the water is moderately hard, hard waters from different sources exhibiting in some cases noteworthy differences in result.

It is the object of the present invention to provide an improved manufacture of the said perborate sodium silicate soap powders, whereby the powders as such will possess greater stability in terms of active oxygen and when used for washing purposes will exhibit greater uniformity of bleaching action whatever the degree of hardness of the water employed.

The invention is based on the discovery that the loss of oxygen from a perborate soap powder containing sodium silicate is greatly decreased by the addition of a small percentage of a suitable salt of magnesium. Thus, it has been found that perborate soap powders containing sodium silicate and magnesium salt lose oxygen far less readily than perborate soap powders containing magnesium salt but no sodium silicate, sodium silicate but no magnesium salt or perborate soap powders alone. In specific tests we have found that if the loss in a given time of oxygen from a perborate soap powder containing sodium silicate and magnesium sulphate be taken as unity the loss of oxygen under similar conditions from perborate soap powders containing magnesium sulphate but no sodium silicate, sodium silicate but no magnesium sulphate and perborate soap powder alone are as follows:—

Powder containing magnesium sulphate (1% crystalline magnesium sulphate) but no sodium silicate	4.3
Powder containing sodium silicate but no magnesium sulphate	2.3
Powder containing neither sodium silicate nor magnesium sulphate	4.3

Suitable salts of magnesium are the sulphate, chloride, and nitrate. Less soluble salts may also be employed, although to less advantage, provided that their fineness of subdivision and thoroughness of incorporation allow their distribution throughout the product to be sufficiently intimate and uniform.

The percentage of magnesium salt to be employed varies to some extent with the nature and proportions of the other ingredients of the powder, but as a rule a quantity thereof equivalent to from about 0.1 per cent. to about 0.3 per cent. of magnesium oxide (MgO) has been found to be suitable.

The incorporation of the ingredients should be thorough and may be effected in various ways. In order to minimize any loss of active oxygen during the process, it is best to avoid temperatures exceeding 50° C. when the perborate has been added.

The incorporation of the magnesium compound employed is facilitated by adding it dissolved or suspended in a small quantity of water. It has been found advantageous first to mix the solution or suspension with the soap while the latter is in a pasty or molten condition and thereafter to incorporate the other ingredients, the perborate being preferably added last in order to minimize the risk of loss of active oxygen.

Example *

To 50 lb. of soap (containing 63% fatty acids) in a pasty or molten condition are added, with thorough mixing, 1 lb. of crystallized magnesium sulphate dissolved in a small quantity of water, 10 lb. of sodium silicate 75° Twad., and 22½ lb. of anhydrous sodium carbonate, and to the resulting mixture, when at a temperature not exceeding 50° C., are added 9½ lb. of sodium perborate, the whole being reduced to powder in the known manner.

We claim:

1. A process for the manufacture of a perborate soap powder containing sodium silicate which process comprises incorporating with the other ingredients of the said soap powder a small proportion of a salt of magnesium.

2. A process for the manufacture of a perborate soap powder containing sodium silicate which process comprises incorporating with the other ingredients of the said soap powder a proportion of magnesium salt substantially equivalent to 0.1 to 0.3 per cent of magnesium oxide (MgO.)

3. A process for the manufacture of a perborate soap powder containing sodium silicate which process comprises incorporating with the other ingredients of said soap powder 0.6 to 1.8 per cent of crystallized magnesium sulphate (MgSO₄·7H₂O).

4. A process for the manufacture of a perborate soap powder containing sodium silicate which process comprises dissolving a soluble magnesium salt in a small amount of water incorporating this solution with the soap when the latter is in the molten or semi-solid condition and thereafter adding the other constituents.
5. A process for the manufacture of a perborate soap powder containing sodium silicate which process comprises suspending a sparingly soluble salt of magnesium in a small amount of water, incorporating this suspension with the soap when the latter is in the molten or semi-solid condition and thereafter adding the other constituents.
- 10 6. A process for the manufacture of a perborate soap powder containing sodium silicate which process comprises dissolving in a small amount of water an amount of magnesium salt equivalent to 0.1 to 0.3 per cent of magnesium oxide (MgO) on the weight of the soap powder, incorporating this solution with the soap when the latter is in the molten or semi-solid condition and thereafter adding the other constituents.
- 15 7. A process for the manufacture of a perborate soap powder containing sodium silicate which process comprises suspending in a small amount of water an amount of a sparingly soluble magnesium salt equivalent to 0.1 to 0.3 per cent of magnesium oxide (MgO) by weight on the soap powder, incorporating this solution with the soap when the latter is in the molten or semi-solid condition and thereafter adding the other constituents.
- 20 8. As an article of manufacture a perborate soap powder containing sodium silicate and a stabilizing substance consisting of a small proportion of a salt of magnesium.
- 25 9. As an article of manufacture a perborate soap powder containing sodium silicate and a stabilizing substance consisting of a salt of magnesium in amount equivalent to 0.1 per cent to 0.3 per cent of magnesium oxide (MgO) on the weight of the soap powder.
- 30 10. As an article of manufacture a perborate soap powder containing sodium silicate and as stabilizing substance a soluble or sparingly soluble magnesium salt in amount equivalent to 0.1 per cent to 0.3 per cent of magnesium oxide (MgO) on the weight of the soap powder inti- mately incorporated therewith.
- 35 11. As an article of manufacture a perborate soap powder containing sodium silicate and as stabilizing substance magnesium sulphate uniformly distributed therein in amount equivalent to 0.1 per cent to 0.3 per cent of magnesium oxide (MgO) on the weight of the soap powder.
12. As an article of manufacture a perborate soap powder containing sodium silicate and magnesium chloride uniformly distributed therein as stabilizing substance in amount equivalent to 0.1 per cent to 0.3 per cent of magnesium oxide (MgO) on the weight of the soap powder.
13. As an article of manufacture a perborate soap powder containing sodium silicate and as stabilizing substance magnesium nitrate uniformly distributed therein in amount equivalent to 0.1 per cent to 0.3 per cent of magnesium oxide (MgO) on the weight of the soap powder.
14. As an article of manufacture a perborate soap powder containing sodium silicate and as stabilizing substance crystallized magnesium sulphate uniformly distributed therein in amount equivalent to 0.6 to 1.8 per cent $MgSO_4 \cdot 7H_2O$ on the weight of the soap powder.

CHARLES WATSON MOORE.
HORATIO BALLANTYNE.

CERTIFICATE OF CORRECTION.

Patent No. 2,004,670.

June 11, 1935.

CHARLES WATSON MOORE, ET AL.

It is hereby certified that error appears in the printed specification of the above numbered patent requiring correction as follows: Page 1, first column, line 53, strike out the character "%"; and that the said Letters Patent should be read with this correction therein that the same may conform to the record of the case in the Patent Office.

Signed and sealed this 14th day April, A. D. 1936.
